UNITED STATES PATENT OFFICE.

PETER KRUSE, OF BROOKLYN, NEW YORK, ASSIGNOR TO E. W. BLISS COMPANY, OF BROOKLYN, NEW YORK, A CORPORATION OF WEST VIRGINIA.

MACHINE FOR WORKING ON CANS.

1,317,926.

Specification of Letters Patent.

Patented Oct. 7, 1919.

Application filed March 21, 1916. Serial No. 85,635.

To all whom it may concern:

Be it known that I, PETER KRUSE, a citizen of the United States of America, residing in the borough of Brooklyn, county of Kings, 5 city and State of New York, have invented certain new and useful Improvements in Machines for Working on Cans, of which the following is a specification.

This invention relates to machines for 10 working on cans, as, for instance, seaming machines, and aims to provide improvements therein.

The present invention embodies an improvement upon that set forth in my United 15 States application Serial No. 54,756, filed October 8, 1915. By the present invention means are provided for "shaping" or "rounding" the cans in seaming, or other position, and there is further provided a 20 combination, or combinations, of such "shaping" means with other elements of the machine, especially the can-feeding mechanism and the end-feeding mechanism. The invention further provides improvements in 25 the end-feeding mechanism.

Other features of improvement will be hereinafter referred to.

An embodiment of the invention is illustrated in the accompanying drawings, in 30 connection with which the invention and its embodiment will be more fully described.

In said drawings,—

Figure 1 illustrates, partly in side elevation and in vertical section, part of a machine for seaming heads on cans, and embodying the present invention.

Fig. 2 is a horizontal section, on the line II—II, of the machine shown in Fig. 1.

Fig. 3 is a diagrammatic view illustrating 40 the action of the feeding means in feeding cans to a working position.

Fig. 4 is a detail view of a part of the end feed mechanism.

In said drawings, letter A designates a 45 mechanism for feeding cans, or can bodies, to a working position, B a mechanism for feeding can heads or ends to the cans or can bodies, C a mechanism for working on the cans, as for instance a seaming mechanism, and D a mechanism for ejecting cans from 50 working position.

The feeding mechanism A preferably comprises a disk *j* having one or more feed-fingers *J* thereon. The disk *j* may be mounted

upon a vertical shaft *j*¹, and may be rotated 55 by a chain and sprockets *j*³, *j*⁴, the sprockets *j*³ receiving motion from a vertical drive shaft *c*.

The feeding mechanism A acts to feed the cans to a position where they are to be 60 acted on by suitable mechanism, as for example the seaming mechanism C.

It is desirable to accurately position cans or can bodies in the working position, and also to "shape" or "round" deformed cans 65 which are fed to a working or other definite position. The positioning, and the shaping or rounding of cans is of advantage in the case where the cans or can bodies are to be supplied with heads or ends, and especially 70 where the heads or ends are supplied to the cans or bodies in a working position, as is preferable in the present invention. The feed-fingers J approximately position the cans in working position. Contiguous to the 75 position of the cans or can bodies in working position there is provided an abutment R, which may be suitably fixed to the casting or column of the machine, and which preferably has a straight edge *r*. Opposite 80 the abutment R there is arranged a movable part S, having a semi-circular, or other appropriately shaped, opening therein, which is adapted to embrace and press the can or can body against the abutment R. 85 By the conjoint action of the abutment R and the movable part S, the cans or can bodies of a degree of deformity capable of being corrected by the machine are accurately positioned and shaped, or rounded to 90 a degree permitting of the reception of the heads or ends.

In the embodiment shown, the machine comprises a pad H which is adapted to lift the cans or can bodies into position to be 95 operated upon by the seaming mechanism C, or other appropriate mechanism for working on the cans. The pad H may be raised and lowered by a slide *h* actuated by a cam piece *h*³ on the rotary shaft *c*.

After the cans or can bodies have been 100 acted upon by the working mechanism they may be fed forward or ejected by suitable feeding or ejecting means D preferably being operatively connected to the main driving mechanism independently of the means for feeding the cans to the mechanism for working on the cans. This means preferably 105

comprises a finger n^7 which is carried by a collar n around an eccentric n^1 fixed on the rotary shaft c . The collar n has a tail-piece n^3 having a sliding connection with a pin n^4 . The action of the eccentric upon the collar n is to give the finger n^7 an elliptical orbital movement. The movement of the finger n^7 is such that after pushing the can or can body from the working position, it 10 moves around, out of the way of the can or can body which may be being fed by the feed arms J , into position to again push a can or can body from working position. The can, when pushed out of working position 15 by the ejecting means, may go on to a deflecting plate P from whence it may pass from the machine.

A means for feeding can heads or ends to the cans or can bodies in working position, 20 is preferably included. This means preferably includes a table m having a suitable magazine or hopper m^1 thereon for holding a stack of can heads or ends, and a slide m^2 . The slide may be reciprocated by means of a 25 rod m^3 , lever m^4 and link m^5 , the rod m^3 preferably receiving motion from a crank disk m^6 which latter may be suitably driven from the rotary shaft c through sprockets m^7 and m^8 , and a chain m^9 . The slide m^2 is provided with an opening m^{10} and has inflected or incurved ends m^{12} . A ledge m^{11} is provided upon which the edges of can heads or ends which are carried by the slide, are adapted to rest.

35 When the opening m^{10} in the slide is beneath the hopper m^1 , a can head or end drops upon the ledge m^{11} , and, upon the slide moving forward, the can head or end resting upon the ledge m^{11} is separated from the 40 other can heads or ends in the stack and carried forward. The movement of the slide m^2 is so timed with relation to the pad H and its actuating mechanism, that the can head or end is lifted from the ledge m^{11} on 45 the slide as the can or can body is moved into position to be worked on by the seaming rolls. When the can head or end is not lifted from the slide by the can or can body, the inflected ends of the slide maintain the can 50 head on the slide, the can head being carried by the slide away from the position where the ends are fed to the cans or bodies. Thereby the actual feeding of the can heads is dependent on the presence of a can or can 55 body to receive it.

As the slide m^2 moves the can head into position over the can or can body, the positioning and shaping means may be arranged to act upon the can or can body, so that 60 the can body is accurately positioned and held to shape, or approximately to shape, when it comes into contact with the can head or end on the ledge m^{11} .

The part S of the can-positioning and 65 shaping means may be conveniently mounted

upon the slide m^2 , as illustrated in the present embodiment.

As the slide m^2 is actuated by a crank, there is a virtual dwell in the slide m^2 , and the part S carried thereby, when these parts 70 are in their forward position to present the can head to be lifted, and to position and shape the cans or can bodies. A stop m^{17} contacting with the end of the slide m^2 effects a positive dwell of the slide in the position thereof with the ledge m^{11} beneath the magazine.

In order to improve the action of the slide 80 m^2 in separating can heads from the underside of the stack in the magazine, the slide is provided with a separator or knife m^{30} (see Fig. 4), and the opening in the slide is pref-

erably made so that the can heads have a sufficient amount of play to fall below the knife edge, and onto the ledge m^{11} . On the feed- 85 movement of the slide, the knife-edge enters between the edges of the lowermost can head in the stack and the one above it, separating the bottom can head or end from the stack. The position of the can head on the slide, as 90 the can head drops from the magazine, is indicated by the dotted line m^{31} , Fig. 4, and the position of the can head on the slide when the knife m^{30} has entered between it and the can head above it, is shown by the 95 full line m^{32} . While the can heads may have a slight amount of play on the slide, yet the inflected ends m^{12} prevent the can head from passing off of the slide edgewise.

Cans or can bodies having a head or 100 end on one end thereof, when deformed, are usually elliptical in cross-section, the ellipse tapering toward a circle when the head or end on the end of the can is circular in shape, and it is advantageous that the 105 deformed can bodies be so positioned in the position where they are acted upon by the positioning and shaping means, that the major axis of the deformed can bodies be in line, or substantially in line, with the direction of motion of the part S of said positioning and shaping mechanism. The feeding means A is preferably such as to accomplish the feeding of deformed cans in such 110 manner that the deformed cans, when approximately positioned, have their major axis in line, or substantially in line, with the direction of movement of the shaping or rounding part.

Referring to Fig. 3, when the feed arm J 120 comes into contact with a deformed can body, the position of most stable resistance to the action of the feed arm will be that in which the minor axis of the ellipse is perpendicular to the feed arm. This relation 125 of the feed arm will continue until the end of the feed arm is in the neighborhood of the minor axis. At this point, and at points of contact between the end of the arm J and the sides of the deformed can body beyond 130

its minor axis, the arm J will act to turn the deformed can body on a vertical axis more or less near one end of the major axis of the ellipse. In this manner the deformed 5 can bodies are approximately positioned with the major axis thereof in line, or substantially in line, with the direction of movement of the movable part of the shaping or rounding mechanism. The non-radial 10 mounting of the arms J on the disk j is of advantage in carrying out the positioning of the deformed can as just referred to. Undeformed cans will be pushed forward in an ordinary manner into position to be acted 15 on by the positioning means, the cans being accurately positioned by the positioning mechanism if they are not so positioned by the feed mechanism.

Features of the invention may be embodied in other machines than a seaming machine. In general, the inventive ideas may receive other mechanical expressions than those herein illustrated and specifically described.

25 What is claimed is:—

1. In a machine of the character described, means for positioning cans in a working position, said means comprising a movable part having an opening therein and adapted to contact with the can body, and an abutment having a straight edge extending to and beyond the working station.

2. In a machine of the character described, means for feeding cans to a working position, and means for positioning cans in a working position, said means comprising a movable part having an opening therein and adapted to contact with the can body, and a fixed abutment acting in conjunction with 30 said movable part, said abutment having an edge parallel to the line of feed of the cans extending to and beyond the working station.

3. In a machine of the character described, means for feeding cans to working position, and means for positioning and shaping cans in a working position, said means comprising a movable part having an opening therein and adapted to contact with, and press 50 to shape, a can body, and a fixed abutment acting in conjunction with said movable part, said abutment having an edge parallel to the line of feed of the cans extending to and beyond the working station.

55 4. In a machine of the character described, means for feeding can heads or ends, and means for shaping or rounding cans or can bodies, said can-head feeding means comprising a reciprocating slide, and said shaping means comprising a part actuated by said reciprocating slide.

5. In a machine of the character described, means for positioning and shaping cans in a working position, said means comprising 60 a movable part adapted to contact with, and

press to shape, a can body and an abutment acting in conjunction with said movable part, and a movable slide for feeding can heads to the cans in working position, said movable part of the positioning and shaping means being mounted upon said feed-slide.

6. In a machine of the character described, means for positioning and shaping cans, said means comprising a movable part having 70 an opening therein adapted to contact with, and press to shape, a can-body, an abutment acting in conjunction with said movable part, a lifting means for can-bodies, a movable can-head carrier, and actuating 75 means for said movable can-head carrier adapted to move it to and from a position over the line of movement of said lifting means, and timed to move said carrier while said lifting means is in its fully lifted position.

7. In a machine of the character described, the combination of means for positioning and shaping cans, means for feeding can-heads to can-bodies when positioned by said 90 means, and means for lifting the can-bodies to lift the can-heads from the can-head feeding-means, said can-head feeding means comprising a slide having means for supporting the edges of can-heads, and a space 95 through which the can-bodies may pass axially and transversely, and means for actuating said slide, said means operating to withdraw said slide while the can is lifted.

8. In a machine of the character described, 100 the combination of means for positioning and shaping cans, means for feeding can-heads to can-bodies when positioned by said means, and means for lifting the can-bodies to lift the can-heads from the can-head feeding-means, said can-head feeding means comprising a slide having means for supporting the edges of can-heads and inflected 105 portions, said slide having a space through which the can-bodies may pass axially and 110 transversely.

9. In a machine of the character described, means for positioning and shaping cans, and means for feeding cans to said 115 positioning and shaping means, said feeding means comprising a feed arm the end of which is adapted to turn a deformed can-body on an axis running through the major axis of the ellipse formed by the deformed can-body.

10. In a machine of the character described, means for positioning and shaping cans, and means for feeding cans to said positioning and shaping means, said positioning and shaping means comprising a 125 movable part adapted to press the can-body to shape, and said feed means being adapted to present a deformed can-body to the shaping and positioning means with the major axis of the ellipse formed by the deformed 130 can-body.

- can-body substantially in line with the direction of movement of said shaping and positioning means.
11. In a machine of the character described, means for feeding can-heads or ends, and a magazine for containing a stack of can-heads or ends, said can head feeding mechanism comprising a movable slide, said slide having a recessed portion adapted to receive and support, and carry away, the separated can-head from beneath the stack, and a knife or separator on said slide for separating the can-head in the recessed portion from the can-heads in the magazine.
12. In a machine of the character described, means for feeding can-heads or ends, and a magazine for containing a stack of can-heads or ends, said can-head feeding mechanism comprising a movable slide, and a knife or separator thereon, said slide having a recessed portion adapted to receive and support, and carry away, the separated can-head from beneath the stack, said knife extending over the edge of said recessed portion for separating the can-head in the recessed portion from the can-heads in the magazine, said recessed portion permitting slight play of the can-head therein.
13. In a machine of the character described, means for feeding can-heads or ends, and a magazine for containing a stack of can-heads or ends, said can-head feeding mechanism comprising a movable slide having a recessed portion adapted to receive a can-head, and a knife or separator on said slide for separating the can-head in the re-
- cessed portion from the can-heads in the magazine, said slide having inflected portions.
14. In a machine of the character described, means for feeding can-heads or ends, and a magazine for containing a stack of can-heads or ends, said can-head feeding mechanism comprising a movable slide having a recessed portion adapted to receive a can-head, and a knife or separator on said slide for separating the can-head in the recessed portion from the can-heads in the magazine, said slide having inflected portions and a space through which can-bodies may pass axially and transversely.
15. In a machine of the character described, means for feeding can heads or ends, and a magazine for containing a stack of can heads or ends, said means for feeding can heads comprising a movable part and a knife or separator on said movable part for separating the lowermost can head from the other can heads in the stack, said movable part having a portion on each side of said knife or separator adapted to support a separated can head, said movable portion being adapted to receive and carry away from beneath the stack the separated can head.

In witness whereof, I have hereunto signed my name in the presence of two subscribing witnesses.

PETER KRUSE.
